HARRY D. DYE, OF SAN FRANCISCO, CALIFORNIA.

REFILLABLE SOAP-STICK.

1,092,436.

Specification of Letters Patent. Patented Apr. 7, 1914.

Application filed August 28, 1911. Serial No. 646,495.

To all whom it may concern:

Be it known that I, HARRY D. DYE, a citizen of the United States, residing at San Francisco, in the county of San Francisco and State of California, have invented a new and useful Refillable Soap-Stick, of which the following is a specification in such full and clear terms as will enable those skilled in the art to construct and use the same.

10 This invention relates to a container for a soap stick, the top or cover of the container being made in a convenient form to serve as a handle when the soap is being used.

Another object of the invention is to provide the soap with a convenient cap whereby the soap may be applied to or removed from the handle at will.

Another object of the invention is to provide a device whereby a little better class 20 of container may be supplied than is possible where the container is sold with each stick of soap. This container may then become of permanent usefulness, it only being necessary to purchase refills for the handle 25 as the supply of soap is exhausted.

Soap is commonly sold with only a paper or tinfoil wrapping, and this affords little protection to the soap stick and is soon softened, distorted or dirty, and is usually discarded before three fourths of it has been used.

This invention seeks to provide mechanical means for holding the soap to the handle, said handle enabling the user to manipulate 35 the soap without actually touching it. Another advantage of the device is that it enables the user to refill the box whenever necessary, capped refills being inserted in the handle when a stick has been used up.

40 A further object of the invention is to provide the means whereby the soap may be securely attached to the cap which secures it in place in the handle. Heretofore many attempts have been made to secure a stick 45 of soap in some sort of a cap, or receptacle by molding or otherwise, but owing to the large shrinkage of the soap after it is molded, it is not possible to secure it in the cap by such a process. It therefore becomes 50 necessary to allow the soap to shrink after it has been molded for a considerable length of time, after which it must be secured in the cap by expanding the same therein, an opening being formed in the cap for that 55 purpose.

This holder gives the necessary grip to

the soap stick for use, and since it may be refilled, it obviates the purchase of a new box and handle with each stick of soap used, the box and handle being used indefinitely, 60 the only expense being the new stick of soap having the metal holding-cap on one end thereof. The box provides a suitable receptacle for the soap when not in use, and since it is purchased but once, it may be a little 65 better than is possible where a new box is sold with each stick of soap, to say nothing of the fact that the user after buying the first box is buying soap instead of a box each time.

70 In the drawings in which the same numeral of reference is applied to the same portion throughout the several views, Figure 1 is a plan view of one-half of one of the soap-holding caps, Fig. 2 is a side elevation of one of the soap holding caps, Fig. 3 is a sectional view of one of the soap holding caps, Fig. 4 is a view of one of the soap sticks having the cap secured thereto, Fig. 5 is a side elevation of the handle for the 80 soap, Fig. 6 shows the soap stick and handle secured together ready for use, Fig. 7 shows the soap stick as it has been spread to secure the same in the holding cap, Fig. 8 is a sectional view showing the soap, handle, and 85 box complete, and Fig. 9 is a sectional view of the device used for securing the cap to the soap stick.

90 The numeral 1 represents the cap, said cap having threads 2 formed therein and having a straight groove 3 formed therearound to secure the soap stick in place. In order to make possible the ready insertion of the soap stick in the cap without the possibility of cutting into the soap on one side or the 95 other, the cap is flanged outwardly as indicated at 4, and since the soap stick is made of the same diameter as the inside diameter of the cap at the groove 3 the stick is very easily placed in the cap, whereupon after 100 being so placed in the cap, the soap 5 is placed in the mold 6 and a blunt instrument 7 is forced through the opening 8 of the cap to spread the soap out into the grooves of the cap at the base thereof. The instrument 105 7 is carried by means of a lever 8, which lever is pivoted to a bracket 9 on the side of the mold 6. It is to be noted that prongs or other securing means are insufficient to hold the small cap and the stick of soap 110 together, it being necessary to spread the end of the soap stick outwardly into the cap

in order to properly secure the two parts together. It is also to be noted that it is not practicable to mold the soap into such a cap for the reason that it is necessary to 5 make the soap of a size larger than the cap, and then to permit the same to cure during which operation the shrinkage of the soap is such as to make impossible the securing of cap and soap together at the time the molding takes place. As accomplished with this 10 invention, the soap is molded of a size larger than will pass into the cap, whereupon it is permitted to cure for such a length of time as may be deemed necessary to allow for 15 considerable shrinkage, after which the soap is placed in the cap and secured thereto as noted herein. When the soap is secured to the cap, the stick may be screwed into the handle 10. This handle is then in turn 20 screwed into the box 11 and the stick is then complete and ready to be set away out of use, or to be used as may be desired.

Having thus described my invention, what I claim as new and desire to secure by Letters Patent of the United States, modifica- 25

tions within the scope of the claim being expressly reserved, is as follows:

A soap-stick holder, comprising a tubular case or box having one end closed and the other end open, an internally threaded cover 30 adapted to fit into said open end and having an extension forming a handle, a sheet-metal holding cap adapted to receive a soap-stick, and having a main annular portion provided with threads indented in the wall of the 35 metal, and having an inwardly-directed flange forming a partially closed top against which the soap-stick may bear but leaving a central opening whereby the material of the soap-stick may be expanded and forced into 40 the threads of the cap.

In testimony whereof I have hereunto set my hand this 22nd day of June A. D. 1911, in the presence of the two subscribed witnesses.

HARRY D. DYE.
